SLIDING PANEL LOCK CONSTRUCTION

Joseph F. Fetyk, New York, N. Y., assignor to
Francis Keil & Son, Inc., a corporation of New
York

Application August 7, 1933, Serial No. 683,963

27 Claims. (Cl. 70—31)

This invention relates to lock construction and more particularly to a construction for locking two relatively slidable closure members such as the sliding glass panels of a showcase, for example.

One of the objects of this invention is to provide a practical and dependable lock construction of the above-mentioned nature that will be of neat appearance and of ease of manipulation. Another object is to provide a construction of the above-mentioned character that is capable of being easily and quickly suited to the various widely varying conditions met with in practice, such as the varying extent of overlap of the sliding panels or closures, the varying thicknesses of the latter, and the like. Another object is to provide a simple, practical, and thoroughly reliable means for securing a lock construction of this character in place. Another object is to provide a lock construction of the above-mentioned nature which may be dependably and securely yet quickly mounted upon or secured to a glass member. Another object is to provide a construction of the above-mentioned type which may be readily and inexpensively manufactured, which may be readily installed, and which will be fool-proof in actual use. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown a preferred embodiment of my invention,

Figure 1 is a front elevation of an illustrative installation of a closure embodying two relatively slidable panels with my lock construction embodied therein;

Figure 2 is a horizontal sectional view as seen along the line 2—2 of Figure 1;

Figure 3 is a horizontal sectional view as seen along the line 3—3 of Figure 1;

Figures 4, 5, 6, 7, 8, and 9 are perspective views of the individual parts that preferably make up my lock construction, the views being vertically arranged in substantially the order in which the parts might be assembled;

Figure 10 is an end elevation as seen from the right in Figure 4 of one of the parts, and

Figure 11 is a fragmentary detached view showing the interlocking of the key with the lock casting.

Similar reference characters refer to similar parts throughout the various views.

Referring first to Figure 1, I have there shown a frame or casing 10 whose upper and lower members 11—12 are shaped in any suitable way to form guideways for the closure members 13—14, the latter being illustratively in the form of sheets of plate glass. The closure members 13—14, hereinafter for convenience termed "panels", when manually moved or slid to the left and right respectively, so as to close the frame or casing 10, respectively abut at their remote ends against the vertical parts 15—16 of the frame or casing 10, the panels 13—14 being so dimensioned that at their adjacent ends they overlap. In Figures 1 and 2 the overlap is clearly visible and for convenience is designated by the distance A. As shown in Figure 1, the panels 13—14 are in closing position. If now the relative sliding movement between panels 13—14 is suitably prevented, access to the space of which the frame 10 forms a part may be precluded.

In practice, whether in existing structures or in structures undergoing manufacture, the overlap A (Figures 1 and 2) frequently varies as does also the thickness of one or both of the sliding panels 13—14. In accordance with my invention, however, I provide a dependable construction not only for preventing relative movement between the sliding panels but also for accommodating such variations met with in practice. Considering now the lock construction per se, reference might first be made to Figure 8 of the drawings. In Figure 8 I have shown an L-shaped plate member B having a flat plate portion 17 generally rectangular in shape and provided at its left-hand end with an upstanding flange 18 preferably formed integrally therewith. The plate portion 17 is relatively speaking preferably of substantial area and a substantial portion thereof is countersunk as at 19 so that a pad 20 (see Figure 7) made of any suitable yielding material, preferably of rubber, may be set into the countersink 19, being preferably cemented thereto and being of sufficient thickness to project above the plane of the surface of the plate portion 17 as viewed in Figure 8. The plate portion 17, thus virtually lined with the rubber pad 20, presents a relatively large area of contact when placed flatwise against one of the panels 13—14, illustratively panel 14 (see Figure 3).

Plate portion 17 (Figure 8) as well as the pad 20 (Figure 7) is slotted along the central horizontal axis of the part B, the slots being shown respectively at 21 and 22 and serving a purpose to be more clearly described hereinafter.

Projecting from the right-hand face of the 55

flange 18 as viewed in Figure 8 are two headed studs 23—24, horizontally spaced from each other, while closely adjacent the junction of the parts 17 and 18, the plate portion 17 is provided with 5 two spaced threaded openings 25—26 (Figure 8) adapted to have threaded thereinto, from the under side of plate portion 17 as viewed in Figure 8, two screws 27—28 (Figures 1 and 3). These screws, as is better shown in Figure 3, are headless while the thickness of the metal of which the part B is made is sufficient to give these screws a substantial range of movement in the threaded openings 25—26 without undesirably projecting to the front of the plane of the front face of 10 plate portion 17 (see Figure 3).

Coacting with the part B is a part C better shown in Figure 5, part C being also L-shaped and made up of a plate portion 29 and a downwardly extending flange portion 30 at its left-hand end. The flange portion 30 is provided with 20 two open ended slots 31—32 spaced apart by a distance substantially equivalent to the spacing of the headed studs 23—24 on the part B (Figure 8) and is of a thickness so that when these studs 25 are received in the slots 31—32 the end flange portion 30 of the part C is snugly received between the flange portion 18 of the part B and the heads of the studs 23—24.

Still referring to Figure 5, the right-hand face 30 of the flange portion 30 is provided with bulges 33—34 spaced and dimensioned so that, when parts B and C are interfitted as above described, the under faces of the bulges 33—34 are juxtaposed to the threaded openings 25—26 in the 35 plate portion 17 (Figure 8) and hence are juxtaposed to the ends of the screws 27—28 respectively (see Figure 3).

The plate portion 29 is cut away or apertured to form a rectangular opening 35 (Figure 5) for a 40 purpose to be described and on its under face, as viewed in Figure 5, it is countersunk as indicated in Figure 5 at 36 in order thus to receive a pad 37 (Figure 6) of a yielding material, such as rubber, adapted to serve a purpose similar to that of 45 the pad 20 associated with the part B, as above described. In Figure 3 the pad 36 will be seen contacting the one face of the panel 14.

The longest dimensions of the end flanges 30 and 18 of the parts C and B, respectively, are 50 substantially the same, so that when the latter parts are interrelated, the end flanges 30 and 18, resting one against the other, virtually mate; as seen in Figure 5, however, the width of the plate portion 36 is somewhat less than the longitudinal 55 dimension of the flange portion 30 and this difference in these dimensions is provided in order more neatly to accommodate a saddle member D (Figures 4 and 10).

The part D comprises a plate portion 38 adapted 60 to rest flat against the upper face of the plate portion 29 of the part C (see Figure 5) and depending side flanges or guides 39—40 (see Figures 4 and 10) which overlap the longitudinal side edges of the plate portion 29 of the part C and 65 guide the part D as it is moved or slid (for a purpose hereinafter described) lengthwise along the part C.

The part D is also provided with countersunk 70 slots 41—42 (see Figures 4 and 10) through which 75 extend screws 43 (see Figure 3) respectively threaded into the threaded openings 44—45 (Figure 5) provided in the plate portion 29 of the part C, the countersinking or undercutting of these slots accommodating the heads of the screws 43, as better appears in Figure 3.

With this slot and screw arrangement, the 5 position of the saddle D lengthwise of the part C may be determined, and fixed when the screws are tightened up; however, this action is utilized to determine the position of a downwardly projecting abutment 46 (Figures 4, 10, and 3) preferably integrally formed with the plate portion 38 of the saddle D and at the left-hand end thereof, as viewed in Figures 4 and 3. This abutment 46 projects downwardly through the rectangular 10 aperture 35 in the part C (see Figure 5) and on its under side or face, as viewed in Figure 10, is provided with a threaded hole 47 which, with the parts B, C and D interrelated as above described and as shown in Figure 3, is juxtaposed to the 15 slot 21 (Figure 8) in the part B; a screw 48, better shown in Figures 3 and 1, passes through the slot 21, the latter being countersunk as shown in Figure 3 to accommodate the head of the screw 48, and is threaded into the threaded hole 47 of the 20 abutment 46 on the part D (Figure 3).

Before considering the various features of coaction of these parts and their relation to and coaction with the sliding panels 13—14, it might first be pointed out, referring again to Figure 8, 25 that the right-hand end portion of the plate portion 17 of the part B is provided with a rectangular opening 49 at two opposed sides of which the inner face (the upper face as viewed in Figure 8) of the plate portion 17 is recessed or cut away or 30 stepped as at 49^a and 49^b; these features are intended to coact with certain other features later herein described.

For coaction with the opening 49 and the stepped recesses 49^a—49^b, I provide a part E, 35 shown in inverted position in perspective in Figure 9, the part E being built up in any suitable way to form a casing 50 whose side walls 50^a—50^b—50^c, and 50^d form a rectangle substantially matching the dimensions of the rectangular opening 49 of the plate portion 17 of the part B in Figure 8 and whose front wall 50^e (the bottom wall, as viewed in Figure 9) is provided with an extension 50^f to the left as viewed in Figures 1, 2, 3, and 9 adapted, when the part E is fitted into 45 the opening 49 of the part B to overlap the front face of the front panel 13 (see Figure 3) the right-hand edge of the panel 13 being intended to be abutted against the side wall 50^b of the part E.

The casing 50 of the part E may be made in 50 any suitable way and preferably is in the form of a casting; its rear wall 50^g (Figure 9) is provided with a slot or guideway 51 in which is slidably mounted a bar or bolt 52, the parts being shaped in any suitable way to interfit, as by dovetailing, 55 for example. The bolt 52 is of a thickness substantially equivalent to the depth of the recess 49^b in the plate portion 17 of the part B (Figure 8) and is of a width substantially equal to the width of that recess; the throw or range of movement 60 of the bolt 52 is substantially equivalent to the dimension of the slot or recess 49^b in the direction of the width of the part B, as viewed in Figure 8.

For coaction with the recess or undercut part 49^a of the part B (see Figure 8) the casing 50 65 (preferably the rear wall 50^g thereof) is provided with an extension 53 (Figure 9) dimensioned to be snugly received within the undercut recess 49^a.

With the bolt 52 withdrawn into its guideway 51, the casing 50 of the part E may be inserted into 70 the opening 49 of the part B by first entering the extension or flange 53 into the recess or seat 49^a and then swinging the casing about this flange 53 as a pivot into the opening 49; if thereafter the bolt 52 is thrown into the position shown in Fig- 75

ture 9, the bolt enters and seats itself in the recess or seat 49°, thus preventing withdrawal of the part E from the part B.

Any suitable means may be provided for controlling or operating the bolt 52 and preferably I provide in the front face 50° of the part E (see Figure 1) a suitable round opening through which extends a key-receiving cylinder 54 provided with a slot 55 for receiving a key 56 (see Figure 11), any suitable connection being provided between the key cylinder 54 and the bolt 52. Merely to indicate such a possible connection, the innermost end of the cylinder 54 (Figure 1) may be provided with a crank arm 57 having a suitable connection 58, such as a pin and slot connection, with the bolt 52 for translating the rotary movement of the key cylinder 54 into movement one way or the other of the bolt 52 along its guideway 51 (Figure 9).

With saddle part D held assembled to the part C by the screws 43 (see Figure 3) and with part C held assembled to the part B by the screw 48 as well as by the headed studs 23-24 (Figure 8), the construction B-C-D may now be fitted to and secured to one of the panels, such as the panel 14, the latter being the innermost of the two (see Figures 3 and 2). A preferred and possible way of achieving this assembly of these parts to the panel 14 may proceed as follows:—

Having determined the amount of overlap A (see Figure 1) between the two sliding panels, screws 43 (see Figure 3) may be loosened up so as to permit the saddle D to be shifted relative to the screws 43 to a sufficient extent to provide a distance or spacing between the right-hand wall of the abutment 46 and the left-hand edge of the opening 49 (see Figure 8) in the part B equivalent to this amount of overlap A; the screws 43 may then be tightened up, thus locking the parts C and D together.

Thereupon the parts D-C-B are slid onto the left-hand edge of the panel 14 (panel 13 being moved to the right for convenience) so that the left-hand portion of the panel 14 is received between the parts C and B (Figure 3), the plate portions 29 and 17 of these parts presenting to the side face of the panel 14 the cushions or pads 37 and 20, respectively, and forming virtually the arms of a U whose base is formed by the abutment 46 against which the left-hand edge of panel 14 abuts.

The abutment 46, moreover, in thus contacting with the left-hand edge of the panel 14 alines the entire construction accurately with respect to the horizontal or vertical, the interfitting guiding parts of the saddle D and the part C and in turn of the parts C and B insuring the proper maintenance of alignment of the various parts in this respect.

Screws 27-28 (see Figures 1 and 3) and 48 are now manipulated, screws 27-28 being unscrewed or screwed in and screw 48 being unscrewed or screwed in or vice versa as the case may be in order to bring the plate portions 29 and 17 of the parts C and B, respectively, toward each other to securely clamp the panel 14 therebetween while maintaining, however, parallelism between these plate portions 29 and 17, thus uniformly to distribute the clamping pressure throughout the relatively large areas through which these plate portions, through the pads 37 and 20, grip the panel 14.

These interrelations between these parts and the control of these interrelations by means of

the screws 27-28 and 48 bring about important practical advantages. Not only is uniformity of clamping pressure achieved, and this is important particularly where the panels are of glass, but also the effect of any possible springing or bending of one or the other of the clamping parts, under the clamping pressure, may be compensated for and thus avoid imperfect gripping or clamping. Depending upon the particular adjustment being made, the screw 48 is virtually the fulcrum when screws 27-28 are adjusted while the latter are the point of the fulcrum when screw 48 is manipulated, and this interchangeability of function and action makes it possible for me quickly and dependably to achieve a uniform and secure clamping action throughout.

Where the panel is of glass, the pads or cushions 37 and 20 (Figures 3, 6, and 7) aid not only toward achieving uniformity of clamping pressure but also, where these pads are of rubber, toward the gripping action directly, having in effect a vacuum cup action in that the clamping pressure drives out the air from in between the pads and the glass surface and thus the effect of atmospheric pressure is added to hold the parts to the glass panel.

The immediately above described features of construction and operation also make it possible readily to accommodate the construction to varying thicknesses of panel in that the screws 27-28 and 48 make it possible to achieve varying distances between the gripping faces of the parts B and C while at the same time making it possible to achieve such parallelism or other relation necessary to achieve uniformity of clamping action or pressure. Thus, the construction may be easily and quickly attached to panels of varying thicknesses. Should the overlap A (Figures 1 and 2) vary, that can be compensated for by a suitable shift in the saddle D and hence in the abutment 46 with respect to the part C and hence with respect to the part B, thus varying the depth of the above-mentioned U and thus bringing the left-hand edge of the opening 49 (see Figure 8) of the part B substantially in line with the right-hand edge (see Figure 3) of the panel 13, when both panels are moved to their extreme left and right-hand portions respectively.

The plate portion 17 of the part B (Figures 2 and 3) is relatively snugly accommodated in the relatively narrow space between the sliding panels 13-14; such a space is practically invariably present in sliding panel constructions of this character and thus the application of the assembled parts D, C and B to the panel 14 does not interfere in any way with the freedom of relative sliding between the two panels.

As above noted, the left-hand edge of the opening 49 in the part B (Figure 8) becomes thus substantially alined with the right-hand edge of the panel 13 (Figures 2 and 3); if, now, it is desired to lock the panels against movement, the part E (Figure 9) is taken and the key 56 inserted therein to withdraw the bolt 52. The key 56 (Figure 11) incidentally, may be of any suitable form or construction and the key-receiving cylinder 54 may be of a corresponding suitable mating construction. A feature, however, that I prefer to employ in any case, is the provision of a slot 56^a (Figure 11) in the key 56 adjacent the outer end of the shank and to provide the front wall 50° of the part E (Figure 1) with a ring 59 having a slot 50^b adapted to mate with the key-receiving slot 55 when the key-cylinder 54 is in

the position with the bolt 52 projected or thrown. Certain unique advantages that flow from these features I mention later hereinafter.

The part E is now inserted into the opening 49 in the part B, it being noted, as is shown in part in Figure 3, that now the front face of the panel 14 forms a bounding wall partially closing the undercut recesses 49^a and 49^b (see Figure 8) into which the projecting flange 53 and the bolt 52 are respectively to be received.

Accordingly, the projecting flange 53 is first inserted into the recess 49^a whereupon the part E is pivoted, as it were, about the flange 53 as an axis, thus to carry the rear face 50^c (Figure 9) into and through the opening 49 and to bear against the front face of the panel 14 (Figure 3). By the same operation or movements, the overhanging part 50^c (Figures 9, 3 and 2) is carried into overlapping relation with respect to the front face of the panel 13 while the end or side wall 50^b (Figure 9) is brought into alignment with and up against the right-hand edge of the panel 13 (see Figure 3).

The key is thereupon turned to throw the bolt 52 into the opposite recess 49^b (Figure 8), the turning of the key bringing the key cylinder 54 into the position shown in Figure 1 where the slots 55 and 50^j come into alignment and thus the key 56 may be withdrawn.

Thus, the panels can no longer be moved with respect to each other and it will be noted also that the overlapping part 50^c so interlocks with the panel 13 and is thereby interlocked with the panel 14 that movement of either panel in a direction transverse of its plane is prevented. Thus, the casing or frame of which the panels 13—14 form the closure is dependably closed and locked closed against unauthorized access to the interior or contents thereof.

In order to facilitate the insertion of the part E as above described, the front face of the part B (see Figure 1) is provided with a suitable marking indicated at 59, outlining on the front face of the part B the shape of the undercut recess or slot 49^a, thus to indicate that, as viewed in Figure 1, the broad or wide flange or projecting part 53 (Figure 9) of the part E should be uppermost when the part E is inserted into or related to the part B.

To unlock the closure, the key is, of course, inserted into the aligned slots 55—50^j and rotated, thus to withdraw the bolt 52 from in behind the plate portion 17 of the part B, whereupon the part E may be swung out of position and removed.

Freedom of relative sliding action of the panels at once results. However, the swinging of the key 56 (Figure 11) into unlocking or unlocked position causes the ring-like flange 50^k (Figures 1 and 11) on the front face of the casing 50 to ride into the slot 56^a on the key shank, whereupon withdrawal of the key is prevented. The key is thus held in assembled relation to the part E which is then placed in any convenient place until such time as it becomes necessary to again lock the closures 13—14; but during that interval, the interlocking of the key with the casing prevents loss of the key so that key and casing are always ready when it becomes necessary to lock the closure.

The parts B, C and D may be and conveniently are of cast metal whereby the various countersinks, slots, recesses, and the like, may be readily cast or formed therein during the casting operation. Thus, the parts may be readily and inex-

pensively made and a relatively small amount of machining need be resorted to.

The saddle D, when clamped by screws 43 (Figure 3) to the part C, as is the case in practice, substantially reinforces the plate portion 29 of the part C, this reinforcement extending also to the side portions of the plate portion 29 that are on either side of the aperture 35 (see Figure 5). The flanges 39—40 (see Figures 4 and 10) extending lengthwise of the saddle D give the plate 10 portion 38 of the saddle D very substantial rigidity and resistance to bending and these strengthening or reinforcing characteristics are, by the above-described clamping action, transmitted and conveyed to the part C itself. Thus, dependable 15 rigidity may be achieved even though the parts are made of relatively light metal stock.

It will thus be seen that there has been provided in this invention a sliding panel lock construction in which the various objects hereinbefore noted together with many thoroughly practical advantages are successfully achieved. It will be seen that the construction is of a thoroughly practical character, is characterized by great ease of installation and manipulation and, moreover, is exceedingly well adapted to meet the many varying conditions met with in practice.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:—

35

1. A construction of the character described, for securing against movement a pair of panel members, one of which is slidable relative to the other and adapted when in closing position to overlap, comprising, in combination, U-shaped 40 means within which an overlapping end of one of said panel members may be received, said means being provided with a plurality of independently operable means for moving one of the arms of said U-shaped means toward the other 45 and to determine the angle between and to bring about and maintain substantial parallelism of said arms, thereby to clamp said one panel member therebetween, one of said arms having a portion extending along said one panel member beyond the overlapping edge portion of the other panel member, a device adapted when related to said extended portion of said arm to coact with said U-shaped means to limit movement of one of said panel members relative to the other, and means 55 for interlocking said device to said extended portion of said arm.

2. A construction of the character described, for securing against movement a pair of panel members, one of which is slidable relative to the other 60 and adapted when in closing position to overlap, comprising, in combination, U-shaped means within which an overlapping end of one of said panel members may be received, means positioned between the base of said U-shaped means and the edge of the said one panel received therein for controlling the angle between the arms of said U-shaped means and for forcing one of the arms of said U-shaped means toward the other, thereby to bring the respective contacting faces 65 of said arms and said one panel member into alignment and to clamp said one panel member therebetween, the arm of said U-shaped means that extends between said panel members extending beyond the overlapping edge portion of the 70 75

- other panel member, and key-controlled means related to said extended portion of said arm and projecting into the plane of said other panel member.
- 5 3. A construction of the character described, for securing against movement a pair of panel members, one of which is slidable relative to the other and adapted when in closing position to overlap, comprising, in combination U-shaped means within which an overlapping end of one of said panel members may be received, said U-shaped means having its two arms movable one toward the other and provided with telescoping means for guiding one arm relative to the other, 10 means for causing the arms of said U-shaped means to grip said one panel member, and means related to said U-shaped means and adapted to be projected into or out of the plane of said other panel member.
- 15 4. A construction of the character described, for securing against movement a pair of panel members, one of which is slidable relative to the other and adapted when in closing position to overlap, comprising, in combination, U-shaped means within which an overlapping end of one of said panel members may be received, one of the arms of said U-shaped means being provided with means for coacting with, and holding against movement, said other panel member, and means 20 for varying the depth of said U-shaped means, thereby to align said last-mentioned means with the edge portion of said other panel member.
- 25 5. In a construction of the character described, in combination, a frame made up of two spaced parts between which a panel member or the like may be gripped, means for adjustably drawing said two parts together, thereby to grip an interposed member, and a block-like member having key-controlled means and having a plurality of 30 projecting members, at least one of which is controlled by said key-controlled means, one of said parts having a recess through which a portion of said block-like member, when said key-controlled projecting member thereof is withdrawn, is 35 passed, said projecting members, when the key-controlled member thereof is projected, preventing removal of said block-like member out of said recess.
- 35 6. In a construction of the character described, in combination, a frame made up of two spaced parts between which a panel member or the like may be gripped, means connecting said parts adjacent one end of each, an abutment between said two parts and intermediate the ends for limiting 40 the depth to which a member may be received therebetween, means for fixing the position of said abutment, means causing said spaced parts to grip a member interposed therebetween, and key-controlled movable means related to one of 45 said parts.
- 45 7. In a construction of the character described, in combination, a frame made up of two spaced parts between which a panel member or the like may be gripped, means connecting said parts adjacent one end of each, an abutment between said two parts and intermediate the ends for limiting 50 the depth to which a member may be received therebetween, means operating upon said abutment for causing said spaced parts to be drawn toward one another to grip an interposed member, and movable obstructing means related to one of said parts.
- 55 8. In a construction of the character described, in combination, a frame made up of two spaced parts between which a panel member or the like 55 may be gripped, means connecting said parts adjacent one end of each, an abutment between said two parts and intermediate the ends for limiting the depth to which a member may be received therebetween, means slidably relating said abutment to one of said parts and for holding it in position relative thereto, means for causing said parts to grip an interposed member, and key-controlled means related to said frame.
- 60 9. In a construction of the character described, in combination, a frame made up of two spaced parts between which a member such as a panel or the like may be received, means movably relating said two parts and adapted to permit variation of the spacing therebetween, means movably related to said frame and interposed between said spaced parts for limiting the extent to which a panel may be received therebetween, and means adapted to coact with a key-controlled means 65 associated with said frame.
- 65 10. In a construction of the character described, in combination, a frame made up of two spaced parts between which a member such as a panel or the like may be received, limiting means extending into the space between said spaced parts 70 for limiting the extent to which an interposed member may be received therebetween, means movably mounting said limiting means, thereby to permit change in its position, and lock means related to said frame.
- 70 11. In a construction of the character described, in combination, a frame made up of two spaced parts between which a member such as a panel or the like may be received, connecting means between said two parts positioned outside 75 of the space occupied by the portion of the panel received between said two spaced parts and operable thereon at two points spaced lengthwise of said frame, one of said connecting means being of variable length, and key-controlled means related to said frame.
- 75 12. In a construction of the character described, in combination, a frame made up of two spaced parts between which a member such as a panel or the like may be received, means positioned outside of the space occupied by the portion of the panel received between said two spaced parts interengaging said two parts at two points spaced lengthwise of said parts, said means being of variable length, and key-controlled 80 lock means associated with said frame.
- 80 13. In a construction of the character described, in combination, a frame made up of two spaced parts between which a member such as a panel or the like may be received, a plurality of means positioned outside of the space occupied by the portion of the panel received between said two spaced parts interengaging said two parts at two spaced points adapted each to act as a fulcrum and each having means for permitting the application through it of a force for moving one member of said spaced parts about the other of said means as a fulcrum, and means related to said frame, for coacting with a key-controlled means.
- 85 14. In a construction of the character described, in combination, a frame made up of two substantially L-shaped members with their respective short arms in sliding engagement, whereby the spacing between the long arms thereof 85 may be varied, means for determining the spacing between said long arms, thereby to accommodate the latter to the reception of one member of a closure therebetween, said means being positioned between the edge of the closure member 90

received therein and that edge of the frame adjacent said short arms, and means associated with said frame and adapted to coact with another member of a closure.

15. In a construction of the character described, in combination, a frame made up of two substantially L-shaped members with their respective short arms in sliding engagement, whereby the spacing between the long arms thereof 10 may be varied, said frame receiving between the free portions of the long arms a closure member, means connecting said long arms intermediate their ends and adapted to function as a fulcrum, means for determining the amount of overlap 15 between said short arms and adapted when operated to swing one of said long arms about said connecting means as a fulcrum, thereby to accommodate said long arms to the thickness of said closure member interposed therebetween, 20 said two means being positioned within the region outside of those portions of the long arms that engage said closure member, and key-controlled means related to said frame and adapted to cooperate with another closure member.
25. 16. In a construction of the character described, in combination, a frame made up of two substantially L-shaped members with their respective short arms in sliding engagement, whereby the spacing between the long arms thereof 30 may be varied, means connecting said long arms intermediate their ends, a screw threaded into one part and abutting against the edge of the short arm of the other part and operable to determine the spacing between said long arms to 35 accommodate it to one member of a closure, and means carried by said frame for coaction with another member of said closure.

40. 17. A construction of the character described, for holding a closure member to a coacting closure member, comprising, in combination, a plate-like member secured to one of said closure members and having a plurality of undercut recesses facing toward the other closure member, a casing member having key-operated means therein and 45 having a plurality of projecting parts at least one of which is controlled by said key-operated means and adapted to be received within said undercut recesses.

50. 18. In a construction of the character described, in combination, a substantially U-shaped means having between the arms thereof a stop member for limiting the extent to which a closure member may be received between said arms, means mounting said stop member for adjustment in a direction to vary the extent to which 55 said closure member may be received between said arms, and key-operated means related to said U-shaped member for coaction with a co-acting closure member.

60. 19. A construction of the character described for securing against movement a pair of panel members or the like, one of which is slidable relative to the other and adapted when in closing position to overlap, comprising, in combination, a frame made up of two spaced parts between which an overlapping end of one of said panel members may be received, means positioned outside of the space occupied by the portion of the panel received between said two spaced parts for engaging said two parts at two spaced points adapted each to act as a fulcrum and having means for permitting the application through it of a force for moving one member about the other of said means as a fulcrum, means substantially telescopically relating said two spaced parts of said frame for movement of said two parts one toward or away from the other, said frame having an extended part extending between said two panel members and beyond the overlapping edge of the other panel member, said extended part being recessed, and a casing- 75

two spaced parts of said frame for movement of said two parts one toward or away from the other, said frame having a part that extends lengthwise of said one panel member and beyond the edge of the other panel member and 5 shaped to coact with a suitable means including a projectable bolt for blocking relative movement between said two panel members.

20. A construction of the character described for securing against movement a pair of panel 10 members or the like, one of which is slidable relative to the other and adapted when in closing position to overlap, comprising, in combination, a frame made up of two spaced parts between which an overlapping end of one of said panel 15 members may be received, means positioned outside of the space occupied by the portion of the panel received between said two spaced parts for engaging said two parts at two spaced points adapted each to act as a fulcrum and having 20 means for permitting the application through it of a force for moving one member about the other of said means as a fulcrum, means substantially telescopically relating said two spaced parts of said frame for movement of said two 25 parts one toward or away from the other, and means related to said frame and adapted to be projected into or out of the plane of said other panel member.

21. A construction of the character described 30 for securing against movement a pair of panel members or the like, one of which is slidable relative to the other and adapted when in closing position to overlap, comprising, in combination, a frame made up of two spaced parts between which an overlapping end of one of said 35 panel members may be received, means positioned outside of the space occupied by the portion of the panel received between said two spaced parts for engaging said two parts at two spaced points adapted each to act as a fulcrum and having 40 means for permitting the application through it of a force for moving one member about the other of said means as a fulcrum, means substantially telescopically relating said two spaced parts of said frame for movement of said two parts one toward or away from the other, said frame having a part that extends between said 45 two panel members and along the face of said one panel member and beyond the overlapping edge of the other and being apertured to receive key-controlled bolt means and for thereby becoming interlocked therewith.

22. A construction of the character described 50 for securing against movement a pair of panel members or the like, one of which is slidable relative to the other and adapted when in closing position to overlap, comprising, in combination, a frame made up of two spaced parts between which an overlapping end of one of said 55 panel members may be received, means positioned outside of the space occupied by the portion of the panel received between said two spaced parts for engaging said two parts at two spaced points adapted each to act as a fulcrum and having 60 means for permitting the application through it of a force for moving one member about the other of said means as a fulcrum, means substantially telescopically relating said two spaced parts of said frame for movement of said two parts one toward or away from the other, said frame having an extended part extending between said two panel members and beyond the overlapping edge of the other panel member, said extended part being recessed, and a casing- 70

like member having key-controlled bolt means, coacting with said recess for interlocking said casing-like member with said extended part and for thereby preventing disengagement between said extended part and said casing-like member, the latter being shaped to overlap the overlapping edge portion of said other panel member, whereby relative movement between said panel members is prevented.

23. In a construction of the character described, in combination, a frame made up of two spaced parts between which a member such as a panel or the like may be received, two means positioned outside of the space occupied by the portion of the panel received between said two spaced parts and engaging said two parts at spaced points, one of said means comprising screw means connected to said two parts to permit said parts to be drawn together and the other of said means comprising screw means in threaded engagement with one of said parts and abutting the other of said parts and thereby adapted to permit said parts to be forced apart, each of said means being adapted to act as a fulcrum whereby, upon manipulation of said two screw means, the angle or parallelism between said two parts may be mated to the angle or parallelism between the faces of the panel respectively engaged thereby, and means related to said frame for coacting with a key-controlled means.

24. In a construction of the character described, in combination, a frame made up of two spaced parts between which a member such as a panel or the like may be received, one of said parts having flange means laterally overlapping the other of said parts, thereby effecting a telescopic relation therebetween, two means positioned outside of the space occupied by the portion of the panel received between said two spaced parts and engaging said two parts at spaced points, one of said means comprising screw means connected to said two parts to permit said telescopically related parts to be drawn together and the other of said means comprising screw means in threaded engagement with one of said parts and abutting the other of said parts and thereby adapted to permit said telescopically related parts to be

forced apart, each of said means being adapted to act as a fulcrum whereby, upon manipulation of said two screw means, the angle of parallelism between said two parts may be mated to the angle or parallelism between the faces of the panel respectively engaged thereby, and means related to said frame for coacting with a key-controlled means.

25. A construction of the character described for securing against movement a pair of panels, one of which is slidable relative to the other and adapted when in closing position to overlap, comprising, in combination, a plurality of means generally U-shaped and within which an overlapping end of one of said panels may be received, one of said means having a part that extends between the overlapping panels and along the face of said one panel and beyond the overlapping edge of the other, said part being adapted to coact with a key-controlled means that is adapted to engage the overlapping edge portion of said other panel and thereby prevent relative movement between the two panels, said plurality of means being slidably related to each other for relative sliding movement in the direction of the thickness of said one panel, thereby to accommodate said U-shaped means to the thickness of the panel, and in a direction lengthwise of said extended part, thereby to accommodate the latter to the amount of overlap between said panels, and means for anchoring said plurality of means against relative sliding movement and for effecting a gripping therebetween of said one panel.

26. A construction as in claim 25 in which the anchoring means includes means positioned outside of the space occupied by the portion of said one panel received between said plurality of means and engaging the latter at two spaced points adapted each to act as a fulcrum and each being of variable length.

27. A construction as in claim 25 in which the anchoring means includes a slot in one of said plurality of means extending in the direction of the overlap of the panels and a clamping screw coacting through said slot to anchor said plurality of means for accommodation of said part to a given overlap.

JOSEPH F. FETYK.
